ALPHEUS W. ALTORFER, OF PEORIA, ILLINOIS

FOLDING WRINGER MECHANISM

Application filed January 4, 1926. Serial No. 79,075.

This invention relates to disappearing wringer mechanism. The object of the invention is in the provision of mechanism which permits the movement of a wringer mechanism to a lowered position or one of non-use, as well as a movement to an upright or operative position, said mechanism including such pivotal connection between the wringer mechanism and the supporting means as to require no adjustments.

Another object of the invention is in the provision of a simple, off-center pivotal connection between the wringer mechanism and supporting means therefor, which permits manual lowering of the wringer mechanism, as well as raising to an operative position, without adjustment.

Still another object thereof is in the provision of a simplified connection between a wringer mechanism and the supporting means therefor that permits manual lowering of the wringer mechanism to an inoperative position, as well as raising same to an operative position, without adjustment, said connection being fashioned to permit the weight of the wringer, when in a raised position, to establish the operative connection with the supporting means.

Other objects of the invention will appear in the following specification, taken in connection with the annexed drawings, in which—

Fig. 1 is a front elevation of a disappearing wringer mechanism, showing its connection with a conventional washing machine, portions thereof being broken away for a more detail showing;

Fig. 2 is an end elevation of the wringer, showing same in raised and lowered positions;

Fig. 3 is a detail showing of the pivotal connecting means;

Fig. 4 is a cross-sectional view taken on the line 4—4 of Fig. 3.

Referring to the drawings, I have shown the disappearing wringer mechanism, as applied to a conventional washing machine of the so-called oscillating disk type. Inasmuch as the present application is directed specifically to the connection of the wringer mechanism with the supporting means therefor, only

a general description of the washing machine is thought necessary.

A supporting frame is shown at 10, this frame being fashioned to support a conventional tub 11, as well as the well known driving means for the oscillating disk 12 therein. In the present instance, the driving connections include an electric motor 13, a belt drive 14 with a pulley 15. The pulley 15 has a driving connection established with the oscillating disk 12 by means of the gear 16, shaft 17, crank 18 and gear 19.

With respect to the driving mechanism for the wringer, a housing member is shown at 20, said housing member including therein a vertically disposed drive shaft, said drive shaft being driven in a conventional manner through a series of gears 22 connected with the above described driving means for the washing machine. The main drive shaft 21 has a suitable bearing 23, adjacent its upper end, which is clutch fashioned as at 24. A conventional wringer assembly has been described, the same including roller members 25, a horizontally disposed drive member 26 therefor, a clutch mechanism 27 permitting movement of the rolls in either direction, and the vertically disposed stub shaft 28, said stub shaft in the present instance having its lower end 29 fashioned in a clutch manner 89 for detachable engagement with the clutch fashioned upper end 24 of the drive shaft 21. The housing 30 of the wringer mechanism, in the present instance, extends merely to a point adjacent the lower end of the stub shaft 28, while, as before described, the housing 20 of the main drive shaft 21 extends also to a point adjacent the upper end of the drive shaft 21.

To permit lowering of the wringer mechanism to an inoperative position, or rather to the dotted line position shown in Fig. 1, applicant has fashioned his connection between the opposed housing members in the following manner. A bracket 34, surrounding the upper end of the housing 30, has the opposed lug members 31 projecting outwardly therefrom in such direction and in such manner as to receive the projecting ends of a bolt member 32, which is supported, as shown in Fig. 100

4, in an outwardly disposed lug 33, which forms part of the bracket 34, said bracket being attached, as at 35 and 36, to the frame of the washing machine. The bracket 34 has, 5 on the side opposite the lug 33, which carries the bolt member, another projecting lug or screw member 37, the same being fashioned in a manner to receive a supporting arm 38, cast integrally with the lower end of the housing 30.

It might be noted that the bolt member 32 is disposed in an angular manner with respect to the adjacent portions, with the result that the wringer mechanism, when lowered, 15 assumes the position shown in dotted lines in Fig. 1, said position not being perpendicular to the vertically disposed drive shaft. This results in such a position for the wringer, when folded, that none of its projecting elements extend beyond the outermost outlines 20 of the machine (note the left side of Fig. 1). The complete unit is therefore more compact by this arrangement and can be conveniently crated. This angular fashioning of the bolt 25 member and connections therefor does, however, permit the vertical alignment of the stub shaft with the main drive shaft when in a raised position, and merely assists in the manual movement of the wringer mechanism 30 to either of its positions.

With respect to the operation of the disappearing wringer mechanism, it is obvious that manual movement of the wringer will permit its being readily lowered to the dotted 35 line position shown in Fig. 1, about the pivotal connection which is established between the housing of the wringer mechanism, and the housing for the vertically disposed drive shaft. It follows naturally that there is a 40 disengagement between the opposed ends of the main drive shaft 21 and the stub shaft 28 in the wringer mechanism. However, and as explained, there is provided a detachable clutch relationship, which permits this movement 45 to the lowered position and the return to a raised position with the respective disengagement and engagement of the clutch faces. It will be also noted that due to the off-centre pivotal connection between the 50 wringer mechanism and the housing, or support 20 for the vertical shaft, the weight of the wringer, when in an upright position, is the means for holding same in an operative position and that there is no attachment 55 means necessary for holding the wringer in this upright position. It is true that the supporting arm 38 engages the lug 37 in a manner to hold the wringer in an upright position, but it is obvious that any abutment 60 mechanism might be used to permit the wringer's assuming an exactly vertical position. However, it is reiterated that the weight of the wringer alone is the only necessary means for holding the wringer in an up- 65 right or operative position, and therefore, all

that it is necessary for the operator to do in moving the wringer to a used or unused position is to move it manually to either of the positions desired.

What I claim is:

1. In combination, a power-actuated driving member, a housing therefor, an inclined pivot carried by said housing, a wringer secured to said pivot for rotation to an upper operative position and to a lower inoperative position, and having a bearing surface engaging said housing at a point disposed laterally of said pivot, a driven member associated with said wringer and adapted to releasably engage said driving member, said wringer being displaced with respect to said pivot in the direction of said point so that the weight of the wringer tends to maintain engagement between said driving member and said driven member. 75

2. In combination, a wringer, a supporting member therefor, an inclined pivotal connection between said wringer and said support, whereby the wringer may be rotated to an upper operative position and to a lower inoperative position, said wringer, when in operative position, being laterally displaced from said connection whereby the weight of the wringer tends to rotate it about the connection, and means for limiting such rotation. 85

3. In a power driven wringer, a vertical shaft, means providing for movement of the wringer about the shaft as an axis, a folding pivot for the wringer inclined with respect to a horizontal plane, whereby when the wringer 100 is rotated on said pivot it will assume a position inclined with respect to the horizontal.

In testimony whereof I have affixed my signature.

ALPHEUS W. ALTORFER.
